UNITED STATES PATENT OFFICE

163,151

CUTLERY HOLDER

Franz Wagner, Chicago, Ill.

Application August 4, 1950, Serial No. 11,603

Term of patent 14 years

(Cl. D44—29)

To all whom it may concern:

Be it known that I, Franz Wagner, a citizen of the United States, residing at Chicago, county of Cook, State of Illinois, have invented a new, original, and ornamental Design for a Cutlery Holder, of which the following is a specification, reference being had to the accompanying drawing, forming part thereof.

Fig. 1 is a top perspective view of a cutlery holder embodying my new design.

Fig. 2 is an enlarged top plan view thereof.

Fig. 3 is an enlarged side elevation thereof.

Fig. 4 is a similar view taken from the side of the device opposite to that shown in Fig. 3.

Fig. 5 is an enlarged end elevational view of the device as it would appear from the right hand end of Fig. 2.

Fig. 6 is a similar view as the device appears when viewed from the left hand end of Fig. 2.

I claim:

The ornamental design for a cutlery holder, as shown.

FRANZ WAGNER.
